CLAIM

The ornamental design for a chair, as shown and described.

DESCRIPTION

FIG. 1 shows a front perspective view of the chair in accordance with the new design.

FIG. 2 shows a rear perspective view of the chair.

FIG. 3 shows a front elevation view of the chair.

FIG. 4 shows a rear elevation view of the chair.

FIG. 5 shows a right side elevation view of the chair, which is a mirror image of the left side of the chair.

FIG. 6 shows a top plan view of the chair; and,

FIG. 7 show a bottom view of the chair.

The broken lines shown in the drawings illustrate portions of the article that form no part of the claimed design.
